(57) CLAIM

I claim the ornamental design for a set of tools for spectacles and packaging, as shown and described.

DESCRIPTION

FIG. 1 is a perspective view of a set of tools for spectacles and packaging in accordance with the present invention;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a perspective view of a set of tools for spectacles and packaging, the tools being shown apart from corresponding portions of a housing; and,

FIG. 9 is a perspective view of one of the tools, the tool being shown with components apart from corresponding attachments.
